UNITED STATES PATENT OFFICE.

DANIEL KOPS, OF NEW YORK, N. Y.

APPAREL-CORSET.

1,170,283.

Specification of Letters Patent. Patented Feb. 1, 1916.

Application filed November 6, 1915. Serial No. 59,915.

To all whom it may concern:

Be it known that I, DANIEL KOPS, a citizen of the United States, residing in the borough of Manhattan, city, county, and State of New York, have invented an Improvement in Apparel-Corsets, of which the following is a specification.

Heretofore and more particularly in the immediate past, there has been a demand for low busted corsets, and in fact, in many instances, instead of a corset garment, women have accustomed themselves to wearing a skirted belt or girdle. In the use of these garments due to their close fitting nature and the customary tension devices, such for example as hose supporters attached to the lower edges of the same, there has resulted, in many cases, a preponderance of flesh over the stomach of the wearer, that is to say, lying between the abdomen and the busts. At the present time the ever changing fashions have a tendency to cause a return demand for the usual corset garment having the regular bust sections as heretofore. In making this change in garments it has been found necessary to provide some means not only to support but to reduce this preponderance of flesh which, as hereinbefore stated has in many cases resulted from wearing an extremely low busted garment or a belt or girdle, and the object of my present invention is the provision of a corset to remedy this effect and also at the same time to properly support the busts.

I am aware that it is not broadly new to place stays in the bust gores of apparel corsets. Heretofore, however, so far as the same has come to my knowledge, stays so placed were merely employed for ordinary stiffening purposes.

In the corset made in accordance with my present invention the stays in each bust gore or section extend from a point in the lower portion of the bust gore somewhat below the waist line and diverge upwardly preferably in correspondingly curved lines, so that the lower front portions of the bust gores and the stays therein lie over any preponderance of flesh there may be between the busts and the abdomen of the wearer. I also employ suitably attached hose supporters which extend downwardly from the front of the garment and when in use exert a downward tension. This causes the front of the garment to act as a lever of the first order with the preponderance of flesh as its fulcrum

and consequently the downward pressure of the hose supporters tends to force the upper portions of the stays outwardly to give form to the bust gore. The reaction of the garment against the portion of the body in which there may be a preponderance of flesh consequently tends to distribute and reduce the same and to force outwardly the upper portion of the stays to give form to the bust gore and to provide a proper and sufficient support for the busts. In the corset made in accordance with my invention, I have found it sometimes advisable to apply the downward and rearward tension directly from the lower portion of each bust section, and, as will be hereinafter described, in other instances, I may also employ a yielding tension strap secured to the corset body or the front portion of the skirts thereof in which construction the forward or free edge of the yielding tension strap is provided with a hook or clasp in order to lend support to the abdomen of the wearer and also to relieve the strain on the lower front portion of the strap sections which in this construction are not connected by a hook or any other means.

In the drawing; Figure 1, is a front elevation of an apparel corset made in accordance with this invention. Fig. 2, is an enlarged elevation of front portion of the corset body half as shown in Fig. 1. Fig. 3, is an enlarged cross section on the line $\alpha\alpha$ Fig. 2. Fig. 4, is an enlarged cross section showing a modified form of the invention. Fig. 5, is also an enlarged cross section showing a still further form of the invention. Fig. 6, is a front elevation of the corset embodying another form of my invention. Fig. 7, is an elevation of the inner side of the same. Fig. 8, is an elevation showing the inside of still another form of my invention. Fig. 9, is a similar view showing another modification, and Fig. 10, is a cross section on line 10—10, Fig. 8.

As will be seen by reference to Figs. 1 to 5 of the drawing, the apparel corset made in accordance with my present invention, comprises as usual the corset body halves 10 and 11 provided along their front edges with steels 12 and clasps 13, and along their rear edges with eyelets 14 through which the usual laces 15 are passed to connect the parts of the garment at the back. The corset body halves are also provided with depending skirts 16 which preferably extend from the

rear to the front medial lines thereof and as shown in the drawing, the garment may also include the front tension straps 17 similar to the corresponding straps shown in 5 Letters Patent, No. 1,127,023, granted to me February 7, 1915. The lower ends of the strap 17 are secured to the lower front edges of the skirt sections to both of which are secured depending hose supporters 18. It 10 being understood that other depending hose supporters may be attached to the lower edges of the skirts in suitable positions.

In each corset body half there is a bust gore or section indicated at 19 extending 15 from the upper edge of the corset to a point appreciably beneath the waist line and each bust gore or section 19 is suitably reinforced or supported by stays or bones indicated at 20 and 21. As shown in the drawing two 20 of these stays are employed extending from the upper edge of the corset at which they are appreciably spaced apart to a point 22 in the lower portion of the bust gore or section and also appreciably below the waist 25 line, it being understood that while I have illustrated two of these supporting stays any suitable number may be employed.

As indicated in Figs. 1, 2 and 3, the stays 20 and 21 may be attached to the outer 30 surface of the bust gore or section by pocket members 23 secured in place by lines of stitches 24 or otherwise. Also as shown in Fig. 4, the bust gore or section in each corset body half may be fitted with an overlying insert 25 between which and the material of which the bust gore or section is made the bones or stays are placed and between the stays the overlying insert 25 may be provided with embroidery or lace indicated diagrammatically at 26. Furthermore 40 as shown in Fig. 5 each bust gore or section may be made double or in two parts 19 and 27 between which the stays 20 and 21 and the pockets containing the same may be 45 placed.

As shown in Figs. 1 and 2, the stay members 20 and 21 preferably are placed in curved lines while substantially diverging toward the upper edge of the garment. Running 50 from the diverging point the stays are slightly curved toward each other and then away from each other and again toward each other adjacent the upper portion of the bust gore. This conformation is found necessary 55 in order that those portions of the stays approximately between the points 29 and 30 which are forced outwardly by the pressure exerted on the garment by any preponderance of flesh there may be over 60 the stomach of the wearer and this forcing outwardly of these portions of the stays tends to spread the upper portions thereof to give form to the bust gore and to provide a suitable support for the bust and as it 65 will be understood the reaction of the gar-

ment against those portions of the body in which there may be a preponderance of flesh tends to distribute and reduce the same. It will, furthermore, be understood that the stays may be placed in other positions to accomplish the same function without departing from the spirit and nature of my invention.

In the structure hereinbefore described the downward tension applied to the lower portion of the bust sections is exerted through the lower front portions of the garment and through the depending strap 17 and the hose supporter 18. In some instances, however, I find it advisable to employ a uniform 80 skirt section, that is to say, a skirt section extending to the front medial line of the garment and to apply the downward pull or tension necessary to effect the desired results directly to the lower portion of the bust 85 section of the garment.

By reference to Fig. 6 and Fig. 7, it will seem that in this construction the garment includes a hose supporter strap 31, the upper portion 32 of which is secured directly to 90 the corresponding lower bust section and being otherwise free from the garment extends downwardly and preferably toward the side of the garment and at its lower end is provided with a hose supporter 33 which 95 passes through a loop 34 secured on the inner side of the skirt adjacent the lower edge thereof in order to maintain the hose supporter strap in its proper position. In this structure the skirts of the corset garment are continuous to the front medial line of the garment as indicated at 35 and below the lower end of the front steels the skirts are provided with members of a hook or other fasteners indicated at 36. In this 100 structure also I prefer to apply hose supporters 37 connected with the lower edges of skirts at the front thereof.

In still further cases, I find it advisable 110 to employ an abdominal tension strap and by reference to Fig. 8 it will be seen that this structure includes the hose supporter strap similar to that described in connection with Figs. 6 and 7, which in this construction may be termed a side hose supporter strap. To this is added a front hose supporter strap 38 also attached at its upper end to the upper end of the side hose supporter strap and the lower portion of corresponding bust section and being otherwise 115 free from the corset body and the skirts thereof and extending downwardly for the greater part in a line substantially parallel to the lower front edge of the skirt member.

39 designates the yielding tension strap which at the end distant from the front edge of the garment is secured to the strap 31 as indicated by a line of sewing or stitches 40 and this portion of the strap 31 as well as the edge of the yielding strap 39 is secured 120

to the skirt section of the garment for the entire width of the yielding tension strap, that is to say, between the lines indicated by 41 and 42. The forward end of the yielding tension strap is connected to the strap 38 by a member of a hook and in Fig. 8 the socket member 43 of a hook is illustrated it being understood that in the corresponding position in the other half of the garment 10 the stud member of the hook is similarly located. In this instance the lower front edges of the skirts are not connected together so that substantially all the strain placed on this part of the garment when the 15 wearer is in a seated position falls upon the yielding tension straps 39 and the hook or other member connecting the same. This permits of a yielding or separation of the front portions of the skirts of the garment 20 when the wearer is seated thereby relieving the strain on the same which they would otherwise have to carry. In this construction the lower end of the strap 38 is connected to one end of a hose supporter 44.

25 Also as shown in Fig. 9 it may be desirable in some instances to dispense with the yielding tension strap 39 and still advisable to employ a double hose supporter strap in each half of the garment. In this construction the hook member, however, may be applied to the lower front edges of the corset skirts leaving the hose supporter straps free from being attached to the garment except at their upper ends as hereinbefore 30 described, or may be attached to the front hose supporter straps, or may be connected to the skirts and also to the front hose supporter straps. Otherwise this construction is the same as hereinbefore described in connection with Figs. 8 and 10.

I claim as my invention:

1. In an apparel corset and in combination with each corset body half, a bust gore or section, stays secured in the bust gore and 45 diverging upwardly from a point in the lower portion of the bust gore appreciably below the waist line, and a strap depending from the lower portion of said bust gore or section to exert a downward tension causing 50 said bust gore or section to act as a lever with the fulcrum at the lower portion thereof thereby applying pressure against the underlying part of the body of the wearer and forcing outwardly the upper portion of the 55 bust gore or section.

2. In an apparel corset and in combination with each corset body half, a bust gore

or section, stays secured in the bust gore or section and diverging upwardly from a point in the lower portion of the bust gore 60 or section appreciably below the waist line and running in correspondingly curved lines to the upper portion of the bust gore or section, and a strap attached at the lower portion of the bust gore or section and extending 65 downwardly therefrom to exert a downward and rearward tension causing said bust gore or section to act as a lever with the fulcrum at the lower portion of said bust gore or section whereby pressure is 70 exerted against the underlying part of the body of the wearer to force outwardly the upper portion of the bust gore or section.

3. In an apparel corset and in combination with each corset body half, a bust gore 75 or section, stays secured in the bust gore or section, diverging upwardly from a point in the lower portion thereof appreciably below the waist line, a hose supporter strap secured to the lower portion of the bust gore 80 or section and extending downwardly therefrom, a second hose supporter strap also secured to the lower portion of the bust gore or section and extending downwardly therefrom, hose supporters secured to the lower 85 ends of the hose supporter straps, a yielding tension strap secured at one edge to the first aforesaid hose supporter strap, and means for connecting the opposite or forward edge of the said yielding tension strap in position for use in the garment.

4. In an apparel corset and in combination with each corset body half, and a depending skirt therefrom, a bust gore or section, stays secured in the bust gore or section and diverging upwardly from a point in the lower portion thereof appreciably below the waist line, a side hose supporter strap, a front hose supporter strap, the said 95 hose supporter straps being secured to the lower portion of the bust gore or section adjacent the lower ends of the stays, hose supporters connected to the lower ends of the hose supporter straps, a yielding tension strap secured at one edge to said side 100 hose supporter strap, and means independent of the skirt for connecting the opposite or forward edge of the yielding tension strap to the front hose supporter strap and by which means the yielding tension straps 105 of the garment are secured together in use.

Signed by me this 29th day of October, 1915.

DANIEL KOPS.
